UNITED STATES PATENT OFFICE.

WILLIAM BENJAMIN FRANKLIN LITTLE, OF BAILEY, ARKANSAS.

ANIMAL-FEEDING DEVICE.

1,286,676.

Specification of Letters Patent.

Patented Dec. 3, 1918.

Application filed May 23, 1918. Serial No. 236,155.

To all whom it may concern:

Be it known that I, WILLIAM B. F. LITTLE, a citizen of the United States, residing at Bailey, in the county of Independence and State of Arkansas, have invented certain new and useful Improvements in Animal-Feeding Devices; and I do declare the following to be a full, clear, and exact description of the invention, such as will enable others skilled in the art to which it appertains to make and use the same.

This invention relates to animal-feeding devices, and it relates more particularly to an improved portable and knock-down feed rack.

One of the objects of this invention is to provide a device of this character which combines great strength and durability, or comparative indestructibility with simplicity, convenience and thorough practicability;

Another object is to provide a device of this character which may be quickly and easily collapsed or knocked down, packed and crated for transportation, and which may be quickly and easily built up for use;

Another object is to provide a device of this character which is portable without being collapsed, and yet not easily overturned or otherwise moved by accident;

Another object is to provide a device of this character which is entirely independent of any extraneous upright support, and which eliminates the use of a partition between animal stalls;

Another object is to provide a device of this character which may be easily constructed by any person of ordinary mechanical ability without the use of expensive tools and machinery;

Another object is to provide a device of this character which consists of few and simple parts, and may, therefore, be constructed at very slight cost.

Other objects and advantages may become apparent to persons who read the following details of description in connection with the accompanying drawings, in which:

Figure 1 is a side elevation of the device which constitutes the preferred embodiment of my invention;

Fig. 2 is a top plan view of the same;

Fig. 3 is a longitudinal central vertical sectional view along the line 3—3 of Fig. 2;

Fig. 4 is an end elevation;

Fig. 5 is a transverse vertical section along the line 5—5 of Fig. 1; and

Fig. 6 is a perspective view illustrating the two forms of sheet metal channel members or trough elements employed in the construction disclosed in the other figures of the drawings.

Referring to these drawings in detail, in which similar reference characters correspond with similar parts throughout the several views, the device consists broadly of three upright supports 7, two sheet metal members 8 and 9, three vertically disposed plates 10, four grating elements 11, rods 12, a central rod 13 and bolts 14.

Each of the upright supports 7 comprises a pair of crossed-bars 15 which are halved at their middle portions and fitted together as indicated at 16 so that two opposite faces of one of the bars 15 are flush with the corresponding surfaces of the other bar of the pair. In other words, these crossed bars are notched or mortised at their middle portions to form shoulders which combine with one another to prevent angular movement of the bars with relation to one another so long as they are fitted together as shown at 16. In order to increase the rigidity of each support 7, its legs are apertured for the reception of bolts 14 which extend therethrough and through corresponding apertures of a bar 18. The bar 18 of each support 7 serves the dual function of supporting the outer side of the sheet metal elements 8 and 9 and rendering the support more rigid. Each of the sheet metal members 8 and 9 is formed with an arch 19 at its middle portion, downwardly diverging elements 20, horizontal elements 21 and vertical outer sides or walls 22. Each of these elements 8 and 9 is notched at 23 so as to receive the crossed portions of the adjacent bars 15, so that the inclined end portions 20 rest upon the inclined or downwardly diverging surfaces 24 of the supports 7 while the horizontal portions 21 rest upon the horizontal bars 18 which extend thereunder from a portion of the supports 7 below their crossing. More-

over, the arch 19 of each member 8 and 9 is supported by the rod 13 which extends thereunder and through alined apertures in the crossings of the supports and in the 5 plates 10. The rod 13 is provided with a head at one end and screw-threads at its other end, and this rod may be in screw-threaded engagement with one of the vertical plates 10, so that by turning the rod by 10 means of its square heads, the several upright supports and sheet metal elements and vertical plates are drawn tightly together so that they form a unitary structure which is easily collapsible by removing the rod 13. 15 I preferably employ a nut on the rod 13 which may coöperate with the adjacent plate 10, or the nut may coöperate with the rod 13 alone for securing the other elements of the device together.

20 From the foregoing, it will be seen that the plates 10 form end walls to the channels formed in the members 8 and 9, so as to combine with these members in forming two troughs at opposite sides of the central rod 25 13. These plates 10 extend to the tops of the supports 7 and also form end walls of the provender racks of which the gratings 11 form the sides. In order to support the provender gratings 11, and also to increase 30 the strength and rigidity of the entire device, the four rods 12 are extended through alined apertures in the supports 7, plates 10 and gratings 11. The rods 12 may be provided with nuts, or they may be in threaded 35 engagement with one of the plates 10, so that they may be operated as has been described for the bolt or rod 13, and may be removed so as to allow removal of the grating elements 11 in the operation of collapsing 40 or knocking down the device.

Although I have described this embodiment of my invention very specifically, it is not intended to limit this invention to these exact details of construction, but I am entitled 45 to make changes within the scope of the inventive idea disclosed in the foregoing description and following claims:

What I claim as my invention is:

1. An animal-feeding device comprising 50 spaced vertical supports, a horizontal rod securing said supports to one another, vertical plates each in a fixed position on said supports, and a sheet metal member having its middle part extending over and supported by said rod and extending laterally therefrom and providing channels which terminate at said vertical plates and combine with the latter to form troughs on opposite sides of said rod, said sheet metal member 55 being movable with relation to said vertical plates.

2. The combination of pairs of crossed upright bars; horizontal bars, each of the horizontal bars being secured to the respective 65 crossed bars of a pair and thereby securing

them in rigid relation to one another; a sheet metal member comprising channels and being supported by said horizontal bars; and a horizontal rod securing said pairs of crossed bars and horizontal bars and sheet 70 metal member together in a unitary structure.

3. The combination of pairs of crossed upright bars; horizontal bars, each of the horizontal bars being secured to the respective 75 crossed bars of a pair and thereby securing them in rigid relation to one another; a sheet metal member comprising channels and being supported by said horizontal bars; vertical sheet metal elements secured to said 80 pairs of crossed upright bars and forming end walls of said channels; and means securing said pairs of crossed bars and horizontal bars and sheet metal member and vertical sheet metal elements together in a unitary 85 structure.

4. The combination of pairs of crossed upright bars; horizontal bars, each of the horizontal bars being secured to the respective 90 crossed bars of a pair and thereby securing them in rigid relation to one another; a sheet metal member comprising channels and being supported by said horizontal bars; and a horizontal rod normally secured to said pairs of crossed bars and being effective to 95 secure said pairs of crossed bars and horizontal bars and sheet metal member and sheet metal elements together in a unitary structure that is collapsible upon removal of said rod, the latter being quickly and easily 10 removable from said crossed bars.

5. The combination of a pair of upright supports each having downwardly diverging-supporting surfaces, and an integral sheet metal member formed with channels and with downwardly diverging surfaces at the ends of the channels, said surfaces of the sheet metal member being normally seated on and supported by the supporting surfaces 11 of said supports.

6. The combination of a pair of upright supports each having downwardly diverging supporting surfaces, an integral sheet metal member formed with channels and with downwardly diverging surfaces at the 11 ends of the channels, and bars secured to said upright supports and extending horizontally beyond the diverging surfaces thereof and supporting the outer sides of said channels, said diverging surfaces of 12 the supports being fitted under the diverging surfaces of said sheet metal member so as to support the inner sides of said channels.

7. The combination of a pair of upright supports each having downwardly diverging-supporting surfaces, an integral sheet metal member formed with channels and with downwardly diverging surfaces at the 13 ends of the channels, bars secured to said 14

upright supports and extending horizontally beyond the diverging surfaces thereof and supporting the outer sides of said channels, said diverging surfaces of the supports being fitted under the diverging surfaces of said sheet metal member so as to support the inner sides of said channels, and a rod normally securing said upright supports together and supporting the middle of said plate.

8. The combination of normally upright pairs of crossed bars; normally horizontal bars, each of said horizontal bars being secured to a pair of the crossed bars below their crossing; a pair of channels normally supported on said crossed bars and horizontal bars; gratings normally secured to the crossed bars above their crossing; and a plurality of rods normally extending from one to the other of said pairs of crossed bars and securing them together and supporting said gratings.

9. The combination of normally vertical pairs of crossed bars; normally vertical

plates disposed on and parallel with said bars; normally horizontal bars, each of the latter being disposed on one of said plates below the crossing of the adjacent bars; means common to each pair of crossed bars and the adjacent plate and horizontal bar for securing them together to form a unitary support; a channeled member supported by the unitary supports thus formed; grating elements each provided with aligned apertures; and rods each normally extending through said unitary supports and aligned apertures of one of said grating elements and securing them together in such relation that said vertical plates combine with said gratings and with said channeled member to form a provender rack and troughs.

In testimony whereof I have hereunto set my hand.

WILLIAM BENJAMIN FRANKLIN LITTLE.
